DESIGN FOR AN AIRCRAFT

Alexander P. de Seversky, Asharoken Beach,
Northport, N. Y., assignor to Seversky Air-
craft Corporation, Farmingdale, N. Y., a cor-
poration of Delaware

Application November 9, 1937, Serial No. 72,715

Term of patent 14 years

To all whom it may concern:

Be it known that I, Alexander P. de Seversky, a citizen of the United States, residing in Asharoken Beach, Northport, county of Suffolk, State of New York, have invented a new, original, and ornamental Design for Aircraft, of which the following is a specification, reference being had to the accompanying drawings, forming a part thereof.

In the drawings,
Fig. 1 is a front elevational view of an aircraft showing my new design;

Fig. 2 is a side elevation thereof, and
Fig. 3 is a top plan view thereof.

I claim:

The ornamental design for an aircraft, substan-

tially as shown.

ALEXANDER P. DE SEVERSKY.
